Inventor

TOWNSEND W. BURT
By his attorney

Herbert H. Thompson

UNITED STATES PATENT OFFICE.

TOWNSEND W. BURT, OF HEMPSTEAD, NEW YORK.

MANDREL PRESS.

Application filed May 29, 1923. Serial No. 642,192.

This invention relates to machines for removing gears, wheels and the like from their shafts, or for mounting the same on their shafts.

5 One of the objects of this invention is to devise a machine which may be used for either of the above named purposes with a minimum amount of changing.

A further object of the invention is to construct a mandrel press which is more simple and quicker to operate than the presses at present in use and at the same time of less cost.

15 A further object of my invention is to improve upon the type of press shown in my copending application for Mandrel presses, Serial No. 563,610 filed May 25th, 1922.

Referring to the drawings in which what I now consider the preferred form of my 20 invention is shown;

Fig. 1 is a side elevation of a press constructed according to my invention.

Fig. 2 is a section taken on the line 2—2 of Fig. 1 looking in the direction of the 25 arrows.

Fig. 3 is a section taken on line 3—3 of Fig. 1 looking in the direction of the arrows.

Fig. 4 is a transverse section on an enlarged angle through the link connecting the 30 operating lever and transverse bar.

Fig. 5 is a front view of the one piece support, stop and guide to which the operating lever is secured.

Fig. 6 is a plan view of the lower workholder, detached.

My apparatus is shown as made up of a stationary support comprising a base 1 and an upright 2 rigidly secured thereto forming a fixed framework or support for the 40 movable elements. The base is shown as secured to the edge of a workbench 3 at one end and as having legs 4 at its other end.

To the upright 2 is pivoted one or more transverse bars 5 and 5' having preferably 45 a plurality of apertures 6, 7 and 8 therein. Between said bars a block 9 is pivotally secured as by a bolt 10 passing through apertures 7 in said bars and a corresponding aperture in said block. As shown, the block 50 has secured thereto on opposite sides thereof, two plates 11 and 12 which take over the bars 5 and 5' (see Fig. 2). In the block is adjustably secured the work engaging member. As shown said member is in the form 55 of a rod 13 threaded in the block 9 and hav-

ing a handle 14 by which it may be turned to lower the same against the work.

Preferably a system of parallel linkage is provided to cause the rod 13 to move parallel to itself about pivot 15 instead of in the 60 arc of a circle. Said linkage is shown as a bar 16 hinged to upright 2 and pivotally connected to plate 11 and to a short link 17, which in turn is pivoted to bar 5. Said bar 16 is also provided with a plurality of apertures 6', 7' and 8' corresponding to apertures 6, 7 and 8 in bars 5 and 5', so that the block 9 may be placed in any of these positions to vary the leverage or to suit the shape of the work.

70 Adjacent the outer end of bars 5 and 5', a link 47 is pivoted thereto. Pivoted to the lower end of the link at 18 is the operating lever 19, which may be forked at its lower end as shown. The operating lever, in turn, 75 is pivoted by a bolt 21 to ears 22 on a plate 23 secured to the base 1. Said plate may also have struck up therefrom ears 24 which act as a guide for link 47 (Fig. 4) and also as a stop to limit the upward movement of 80 lever 19.

75 The workholder proper is shown as formed of a plate 25 having a central aperture 25' and turned up at opposite edges to form guides 26, 27 which take over parallel bars 28, 29 forming the base (Fig. 3). The workholder may also be provided with a second base or plate 30 adjustably supported by a pin or pins 31 extending through any pair of a plurality of apertures 32 in parallel bars 85 33, 34. Said base 30 is also provided with a central aperture 35 which may be closed by pivoted strip 36. Slots 37 and 38 are shown in the base through which bars 33 and 34 pass.

90 To use my mandrel press for removing a shaft from a gear (for example) the gear is placed on plate 25 with the shaft extending through aperture 25'. After adjusting the plate 25 to a position under rod 13 and 95 adjusting the rod to engage the gear shaft, the operating lever is lowered to remove the shaft. By means of the long lever arm of lever 19 multiplied by the leverage of bar 5, 5', a very powerful pressure may be exerted 100 with a minimum exertion on the part of the operator.

105 When using the press to apply a shaft to a gear, the shaft may be placed on the lower work holder 30 with the aperture 35 closed 110

2
by strip 36 so that the shaft extends upwardly through aperture 25' and is guided thereby. In this case, the lower end of rod 13 is provided with a bell-mouthed work engaging member 40. To press the gear on the shaft, it is placed on the top of the shaft and rod 13 with member 40 attached thereto lowered to apply the gear in the same manner that was described in removing the gear.

19 In accordance with the provisions of the patent statutes, I have herein described the principle of operation of my invention, together with the apparatus, which I now consider to represent the best embodiment thereof, but I desire to have it understood that the apparatus shown is only illustrative and that the operation can be carried out by other means. Also, while it is designed to use the various features and elements in the combination and relations described, some of these may be altered and others omitted without interfering with the more general results outlined, and the invention extends to such alterations.

25 Having herein described my invention what I claim and desire to secure by Letters Patent is:

1. In a press, the combination with a workholder and a work engaging member, a transversely extending bar supporting said member, a support on which said bar is pivoted adjacent one end, a link pivoted to said bar at a point spaced from said support, a base, a plate secured to said base and having two pairs of upturned ears, and an operating lever pivoted between one pair of said ears and to said link, the other pair of said ears serving as a guide for said link.

2. In a press, a support, a substantially horizontal bar pivoted thereon, a member

slidably mounted on said bar, means for securing the same in a desired position, a work-engaging member threaded therein, a lever mechanism for operating said bar, and a work-holder slidably mounted on said support. 45

3. In a press, the combination with a work engaging member and a work holder positioned adjacent thereto, a transversely extending bar supporting said member, a support on which said bar is pivoted adjacent one end, a linkage pivoted to said supporting member and bar for causing the member to move parallel to itself, a link pivoted to said bar at a point spaced from said support, 50 a base for said support and an operating lever pivoted on said base and to said link.

4. In a press, the combination with a supporting base, of a transverse bar pivoted thereto, a work engaging member adjustably mounted thereon, an operating lever pivoted on said base, means connecting said lever and bar and a workholder adjustably mounted on said base. 60

5. In a press, the combination with a workholder and a work engaging member, a transversely extending bar supporting said member, means whereby said member may be secured in any one of a plurality of positions along the bar, a support on which said bar is pivoted adjacent one end, a linkage pivoted to said supporting member and bar for causing the member to move parallel to itself, a link pivoted to said bar at a point spaced from said support, 65 a base for said support and an operating lever pivoted on said base and to said link. 70

In testimony whereof I have affixed my signature:

TOWNSEND W. BURT.
